COMBINED VEHICLE SAFETY LIGHTS ENSEMBLE AND MOUNTING BRACKET THEREFOR

Ladell P. Olson and Frank P. Cooley, Eagle Grove, Iowa,
assignors to Rycol Corporation, Eagle Grove, Iowa

Filed May 26, 1972, Ser. No. 257,485

Term of patent 14 years

Int. Cl. D26—06

U.S. Cl. D48—32 R

Fig. 1

Fig. 2

Fig. 3

FIG. 1 is a front view of a combined vehicle safety lights ensemble and mounting bracket therefor showing our new design,

FIG. 2 is a side view thereof, the opposite side being identical.

FIG. 3 is a rear view thereof.

We claim:

The ornamental design for a combined vehicle safety lights ensemble and mounting bracket therefor, as shown and described.
